PAUL CZIGLER, OF SZÉKES-FEJÉRVÁR, AUSTRIA-HUNGARY.

KILN FOR BURNING BRICK, LIME, AND SIMILAR MATERIAL.

No. 877.300.

Specification of Letters Patent.

Patented Jan. 21, 1908.

Application filed December 29, 1906. Serial No. 349,969.

To all whom it may concern:

Be it known that I, PAUL CZIGLER, a subject of the Emperor of Austria-Hungary, residing at Székes-Fejérvár, county of Fejer, 5 Austria-Hungary, have invented new and useful Improvements in Kilns for Burning Bricks, Lime, and Similar Material, of which the following is a specification.

which the following is a specification:
This invention relates to a kiln which is
10 particularly adapted for burning bricks and
lime, but may also be satisfactorily employed
for other suitable materials.

for other suitable materials.

The kiln is so constructed that the fuel
may be practically completely utilized
therein by compelling the fire gases to be
repeatedly circulated through the kiln after
the escape of the waste gases, thus com-
pletely giving up their heat. For this pur-
pose, the inclosure wall of the kiln is pro-
vided with channels or passages branching
from the channel in the bottom and extend-
ing beneath the burning banquets. The
fire gases pass out of the aforesaid channels
into the continuous channels in the roof of
the kiln and from the latter channels into
the open air, thus giving up their heat.
When the firing is completed, the available
hot gases may be led into a neighboring
kiln for preheating the same. A kiln con-
structed according to this principle has, in
addition to its considerable saving of fuel,
proved by experiments, the great advantage
that the burning proper and the drying take
place more rapidly than in any other
annular kiln which has hitherto been con-
sidered most suitable for this purpose.
While having the same capacity, the kiln
requires a much less investment of capital
and a much less working expenses.

and generally much less working expenses.
40 The kiln forming the subject matter of the invention is shown in the drawing in two forms of construction and in Figures 1-3 for burning bricks and lime.

Fig. 1 is a longitudinal vertical section 45 of the kiln; Fig. 2 is a plan and Fig. 3 is a cross-section at an angle of 90° to Fig. 2. Details of a kiln are shown in Figs. 4-6, which is adapted for burning materials (such as porcelain or the like) requiring 50 more careful treatment. Fig. 4 shows a part of the kiln in a similar view as Fig. 2; Fig. 5 is a section on line A—B of Fig. 4 and Fig. 6 a section on line C—D of Fig. 4. Fig. 7 shows an arrangement how the gases 55 ascending in the channels are employed for preheating a neighboring kiln.

The kiln which in plan is circular, or oval as shown, or of any other shape, is provided at its bottom 1 with several channels 2 extending outwardly and arranged at regular distances apart from each other. These channels 2 are covered above within the inclosure wall 3 by inclined grates 4. The grates rest with their inner end upon the bottom 1, while the other end bears upon the intermediate roof 6 fixed in the elevated wall-opening 5. The arched chamber above the roof 6 serves for charging the kiln, while the bottom space 7 together with the space over the grate forms the ash pit, the draft or current of air passing through 5, 7. The wall openings may be wholly or partially closed by doors not shown in the drawing.

There is provided in the bottom 1 along the middle line of the kiln a gutter 8, both ends of which are somewhat enlarged. Channels 9 communicate with this gutter 8 and extend therefrom under the banquets between the grates to the wall 3, then upwards along the arched wall 3 to the roof-wall 10 of the kiln and extend from here upwards along the two roof-walls, as shown in Fig. 3. The roofing of the kiln is divided by two longitudinal walls 11 and there are formed between these walls at a suitable distance from each other channels 12 which lead below into the inner chamber 17 of the kiln. The intermediate walls do not reach to the level of the roof-walls 10 so that a space or chamber 13 is left over the same.

The external roof 14 adapted to be raised and lowered in the usual manner is provided above on the roof-wall of the kiln.

The channels 9 are provided above the wall 95
5 and the channels 12 where they communicate with the kiln chamber 17 with sliding doors 15 adapted to be operated from without. Moreover, the inclosure wall is provided with one or more peep holes 16 covered by specular gypsum or the like in the usual manner. 10

The operation is as follows: After placing the bricks or the like to be burned upon the banquet *i. e.* after setting the kiln, the firing operation is commenced whereupon the spaces or chambers 7 beneath the grates and the channels 9 and 12 as well as the external roof 14 are kept open. At the commencement of the firing, the waste gases are withdrawn through the channels 12 which latter are kept open until the waste gases are with-

drawn completely purified. The wall openings 7 the channels 9 as well as the roof 14 remain open during the firing operation. After shutting off the channels 12, the fire 5 gases coming from the grate fires supplied with a regulated draft of air are drawn up along the inner wall of the kiln to the top of the inner chamber 17 and from thence into the bottom gutter 8, then through the channels 10 9 branching from the gutter 8 under the banquet and from here along the inclosure wall 3 through the roof 10 and the chamber 13 into the open air. After firing for about 16 hours, the outer rod 14 is lowered, the 15 channels 9 and the wall apertures 7 are shut off and the kiln left standing for two to three times twenty four hours; after the expiration of this period, the channels 12 and the channels leading from the chamber 13 to the 20 neighboring kiln, which were closed during the entire firing operation are opened, so that the available hot gases pass over into the neighboring kiln and preheat the same. These channels are not shown in the drawing. After a certain while, all channels are 25 opened and the outer roof raised for cooling the material.

If materials which require more careful treatment, such as porcelain or the like, are 30 to be burned, the fire-place must be so constructed that the fire gases and incoming cold air do not come in direct contact with the material to be burned; such an arrangement is shown in Figs. 4-6.

35 The bottom 1 is raised to such an extent that the arch of the wall-opening 5 is approximately level with the floor. Consequently, the chamber above the grate is arched and this arch is provided with holes 40 18. The burning banquets are provided with channels 19 open above and terminating at two sides in the spaces above the grates. In consequence of this arrangement, the cold current of air entering through the 45 wall openings 5, 7 cannot come in contact with the materials to be burned, so that these cannot crack, and the fire gases coming from the grate can also not come in direct contact with these materials.

50 The draft of air in the kiln may also be increased in that there are air draft channels 20 in the inclosure wall leading from the wall-openings 5, 7 to the grates, as shown at one part in Fig. 2.

55 The shape of the kiln, the construction of some parts thereof and the arrangement of the regulating devices may undergo alterations without departing from the spirit of the invention. The essence of this invention 60 consists in forming in the bottom, in the inclosure wall and in the roof of the kiln, channels which communicate with one another, so that the fire gases repeatedly circulate

through the kiln and thus completely give up 65 their heat.

Referring to Fig. 7 it will be seen that there branches from the chamber 13 or near thereto a channel 21 (or several channels) leading along the kiln wall in any suitable manner to the middle gutter 8 of the neighboring kiln. 70 The mouth of this channel near to the chamber 13 is closed during the firing of the kiln— when the roof is raised as shown in Fig. 3— and is only open when the roof is lowered, so that during the simultaneous opening of this 75 channel communicating with the gutter 8, the gases pass in the directions as indicated by arrows out of the kiln I into the kiln II. The simultaneous uncovering of the upper mouth of the channel 21 with the lowering of 80 the roof 14 can be effected in different ways. In the drawing, for example, the closing plate 22 for this mouth participates in the movements of the roof and is provided with a window aperture arranged in such a manner 85 that the latter comes in front of the mouth of the channel when the roof is lowered, while when the roof is raised, the full surface portion of the plate 22 shuts off the channel mouth.

Having now particularly described and ascertained the nature of my said invention and in what manner the same is to be performed, I declare that what I claim and wish to secure by Letters Patent is:

1. A kiln for burning bricks and the like 95 comprising a bottom having a trough 8 therein and channels 9 leading from said trough to the sides of the bottom, an inclosing wall having channels therein forming continuations of the channels 9, a roof having a 100 chamber therein into which the channels of the walls lead, said roof having channels 12 therein leading from the chamber into the kiln, and a movable roof for closing or opening said chamber to the atmosphere, substantially as described.

2. A kiln for burning bricks and the like comprising a bottom having a trough 8 therein and channels 9 leading from said trough to the sides of the bottom, an inclosing wall having channels therein forming continuations of the channels 9, a roof having a chamber therein into which the channels of the walls lead, said roof having channels 12 therein leading from the chamber into the 115 kiln, a movable roof for closing or opening said chamber to the atmosphere, and doors 15 for controlling the channels 9 and 12, substantially as described.

In testimony whereof I have signed my 120 name to this specification in the presence of two subscribing witnesses.

PAUL CZIGLER.
